UNITED STATES PATENT OFFICE.

WILLIAM CEPHAS GRIFFITH, OF MERRILL, OREGON.

MEANS FOR CONNECTING EXCAVATING SCOOPS OR SHOVELS TO TRACTORS.

Application filed July 18, 1922. Serial No. 575,865.

To all whom it may concern:

Be it known that I, WILLIAM C. GRIFFITH, a citizen of the United States, residing at Merrill, in the county of Klamath and State of Oregon, have invented new and useful Improvements in Means for Connecting Excavating Scoops or Shovels to Tractors, of which the following is a specification.

This invention relates to excavating scoops 10 or shovels, and more particularly to the means for attaching the same to tractors to be drawn by the latter during operation.

The object is to provide a shovel or scoop, 15 tiltably connected at the rear ends of draw bars so that the same may be tilted or dumped to discharge its contents, said tilting as well as the finer adjustments for the depth of cut being controlled by an operator trailing the scoop, the said draw bars being 20 hingedly connected at their front ends to vertically adjustable pivots to more properly adapt the scoop to the proper position for doing its work.

A further object is to provide means for 25 connecting the draw bars at an intermediate point to elevating means carried by the tractor, said means being automatically engaged or connected with the elevator when the scoop is emerging from a ditch or declivity so as to lift the load of dirt free of 30 the ground, if desired, and also to enable the machine to be pushed backwardly again for a fresh load.

Another object is to provide such connecting means which may be instantly disconnected from the draw bars of the scoop by pressure from the foot of the operator riding on the foot boards of the tractor, so that the scoop is free to enter the starting end 40 of the ditch, or at any other point, after the same has been carried back to such point by the tractor, thus obviating the necessity of turning the tractor around.

A full and complete understanding of the 45 invention may be obtained from a consideration of the following detailed description, taken in connection with the accompanying drawings forming a part of this specification, it being understood that while the 50 drawings show a practical form of the invention, the latter is not confined to strict conformity therewith, but may be changed or modified, so long as such changes or modifications mark no material departure 55 from the salient features of the invention,

as specifically pointed out in the appended claims.

In the drawings, in which similar reference characters designate corresponding parts throughout the several figures: 60

Figure 1 is a side elevation of the rear end of a tractor having a shovel or scoop embodying the improvements attached thereto.

Figure 2 is a detail perspective view of 65 the draw bars of the scoop and showing the means of connection to the tractor.

Figure 3 is a transverse sectional view 70 through the draw bars and showing their connection to the lifting lever.

In operating shovels or scoops of the character herein shown and described, the difficulty has been to be able to pick up the scoop after dumping the same, and while free of the ground, to run back to the starting point for another load, it being only necessary to reverse the tractor which moves in both directions in straddling relation to the ditch. Another desirable feature is to be enabled to guide the cutting edge of the 80 scoop so as to take a greater or lesser cut, and to dump the same at any point, as in levelling work, and to be enabled, during the operation of ditching or forming trenches, etc. to detach the elevating means so that 85 the scoop will fall below the level of the ground and remove the dirt at the bottom of a ditch of considerable depth, the said scoop automatically engaging itself with the connecting means carried by the elevator 90 when it reaches the incline at the end of the ditch, and raised by the same to be carried to a distant point or to be dumped at any other desired point.

To this end the invention comprises a 95 pair of spaced draw bars 1 formed of some suitable strong metal, preferably rectangular in cross section, and of sufficiently large dimensions to give the required strength for withstanding the great strain to which they 100 are subjected in operations of this kind, angle iron bars may, however, be used to equal advantage in the construction of the draw bars if desired.

The draw bars 1 are similarly formed and 105 are provided intermediate of their ends with downwardly bent portions 2, the lower ends of the bars being provided with bolt openings 3, through which pivotal bolts 4 are adapted to pass for the purpose of hingedly 110

connecting a scoop 5, which may be of any desired form and construction, the said scoop forming no part of the present invention. The scoop is preferably provided with 5 the usual angularly bent runners 6 at either end of the same and operating handles 7 suitably secured to the rear closed side of the scoop, and extending rearwardly and upwardly therefrom, so as to be within 10 reach of an operator who walks along behind the scoop in the ordinary manner, it being understood that the front, open or active side of the scoop is directed toward the other ends of the draw bars, which 15 constitute the front ends of the same and which are connected to the rear end of the tractor.

The front ends of the draw bars 1 are connected together by a transversely disposed angle bar 8, held to the ends of the 20 same by headed screws 9, and further strengthened by an angularly bent bracket having an intermediate portion 10 adapted to be bolted to the intermediate portion of the angle bar 8, as at 11, and angular end 25 portions 12 terminating in feet 13 which are bolted to the inner sides of the draw bars 1, as at 14, the bracket thus serving to maintain the draw bars in their spaced, 30 parallel positions with relation to each other.

Adjustably secured to the upper edges of the draw bars 1, at any desired point between the rear ends of the feet 13 and the upper or forward ends of the inclined portions 2 of the same, is another transversely disposed angle iron 15 extending, like the front angle iron 8, somewhat beyond the outer faces of the draw bars, and the angle iron 15 is held to the draw bars by means 35 of U-bolts 16, the latter serving also to bind the foot portions 17 of a bail or loop 18, which extends upwardly and inwardly to form an engaging portion at the longitudinal center line between the draw bars.

45 The front angle iron 8 is provided with a plurality of bolt openings 19 for the reception of bolts 20 which connect the draw bars, together with the scoop, to a clevis 21 having pivotal connection to the rear 50 end of a draw link 22, which, in turn, is pivotally connected as at 23 to the frame of the tractor at a point slightly in advance of the rear axle 24 thereof, and at the under side of said frame.

55 The clevis 21 is also connected to the lower end of a lifting link 25, having its upper end pivotally connected to a crank member 26, forming a part of a transversely disposed shaft mounted on the upper side of 60 the tractor frame, and actuated by a hand lever 27, which may be manipulated to raise or lower the clevis 21 at will, in order to position the front ends of the draw bars at the desired elevation.

65 Mounted at the rear end of the main

frame of the tractor is a lifting dog 28 pivotally connected, at 29, to rock vertically, through the pulling action of a link 30, connected to suitable means for actuating the same under load, and to cause the rear end 70 of the lifting dog 28 to rise to the dotted line position shown in Figure 1 when rocked about its pivotal point 29.

Pivoted, as at 31, to the rear end of the lifting dog 28, is a connecting link or lever 32, which is adapted to rock about its pivot 31 in the bifurcated end 33 of the said dog, and the lever 32 is provided at its upper end with a flat portion 34 arranged transversely to the frame of the tractor, and free to be reached and operated by the foot of the tractor attendant, to cause the lower end of the lever 32 to be moved in a forward direction.

The lower end of the lever 32 is provided with a rearwardly directed bill or hook 35 adapted to engage with the bail 18 carried by the draw bars 1 and to support the same in a substantially horizontal position, as indicated in Figure 1 of the drawings.

With the parts connected as shown in Figure 1, the forward, open and active end of the shovel or scoop 5 is in a position to do levelling work upon the surface of the ground, the fluctuations necessary in the elevation of the cutting edge of the scoop being readily accomplished by simply tilting the same about the bolt 4 through the medium of the handles 7, in the ordinary manner. When it is desired to dump the load on the level, it is only necessary to throw the scoop over on the runners 6 at the desired point, and in the event it is desired to lift the scoop load and carry the same to a distant point, the lifting dog 28 may be rocked about its 100 pivot by means of the link 30 to cause the bill of the hook 35 at the lower end of the lever 32 to automatically engage the bail 18, when the lifting link 30 may be actuated to lift the draw bars, scoop and load to the elevated position, indicated in dotted lines in Figure 1, the said draw bars swinging about their forward pivotal points at the lower end of the link 25.

In the operation of ditching, the hook 35 is disengaged from the bail 18, when the scoop may follow the downward course of the entrance to a ditch, or may be dropped bodily into the same at any point, the front ends of the draw bars swinging downwardly 115 about their pivot, and the links 22 will still serve to give the necessary pull to cause the scoop to receive its load whereupon, when the other inclined end of the ditch is reached, the scoop may be guided by the following operator to travel up the same, when the bail 18 will swing upwardly in the path of the curved bill of the hook 35, and the latter will automatically engage the same 120 and the dog 28 may be operated to lift the 130

load clear of the ground, if desired, or the same may be dragged along the surface of the ground and dumped at any point.

No claim is made herein to the structure 5 of the tractor, nor to the lifting mechanism carried thereby, including the hand lever 27 and parts directly connected thereto, the dog 28 and actuating means for the same, these parts being common to the well known 10 Heider tractor, but it is to be understood that the present invention may be as advantageously connected to and operated in conjunction with other means capable of accomplishing the desired results.

15 From the foregoing it will be seen that a simple, durable, easily manufactured excavating scoop or shovel supporting frame has been provided, and means for connecting the same to elevating means carried by a 20 tractor, whereby the said scoop may be manipulated in a manner to effect a great saving in the operations of levelling ground or in forming trenches or ditches for irrigation purposes; etc., and that the same may 25 be easily attached in position for work, or detached from the tractor when desired.

What is claimed is:—

1. A device of the class described, comprising spaced, parallel draw-bars adapted 30 to be pivotally connected at their lower, rear ends to an excavating scoop, a transverse member connecting the spaced, forward ends of the bars and adapted to be connected to a tractor, an intermediate transverse 35 bar adjustably mounted on the draw bars, an upstanding bail carried by the intermediate, transverse bar, and a lifting lever adapted to be fulcrumed intermediate its ends, on the tractor, said lever being provided with a foot plate at its upper end for 40 rocking the same and having a hook at its lower end for engagement with the said bail to support the draw bars and scoop.

2. A device of the class described, comprising spaced, parallel draw-bars provided 45 intermediate their ends with inclined portions and adapted to be pivotally connected at their lower, rear ends to an excavating scoop, a transverse member connecting the 50 spaced, forward ends of the bars and adapted to be connected to vertically adjustable

pulling means carried by a tractor, an intermediate transverse bar adjustably mounted on the draw bars between the forward ends and the inclined portions of the draw bars, an upstanding bail carried by the intermediate, transverse bar, and a lifting lever adapted to be fulcrumed intermediate its ends to a lifting dog mounted for rocking movement on the tractor, said lever being provided with a foot plate at its upper end for rocking the same and having a hook at its lower end for engagement with the said bail to support the draw bars and scoop. 65

3. In combination with a tractor having a lifting dog, a lever pivoted to the dog and having a hook at its lower end directed rearwardly, a scoop, draw bars supporting the latter, means for connecting the forward 70 ends of the draw bars to the tractor, and a bail on the draw bars adapted to automatically engage the hook.

4. In combination with a tractor having a lifting means, a lever carried by said means and provided with a hook, a scoop, draw bars, means for flexibly connecting the front ends of the draw bars to the tractor, means for pivotally connecting the rear ends of the draw bars to said scoop, and means carried by the draw bars to be automatically engaged by said hook, whereby the draw bars and scoop may be raised above the ground. 80

5. In combination with a tractor having 85 a lifting means, a lever carried by said lifting means and provided with a hook and a foot plate for rocking the lever on its pivot, a scoop, spaced draw bars, means for flexibly connecting the front ends of the draw bars 90 to the tractor, means for pivotally connecting the rear ends of the draw bars to said scoop, and an upstanding rigid bail carried by the draw bars intermediate of their ends, said bail being automatically engaged by 95 said hook, whereby the draw bars and scoop may be raised above the ground.

In testimony, that I claim the foregoing as my own, I have hereunto affixed my signature.

WILLIAM CEPHAS GRIFFITH.
